UNITED STATES PATENT OFFICE

102,337

DESIGN FOR A SIGNBOARD OR SIMILAR ARTICLE

Lee B. Sapp, Lexington, Ky.

Application July 28, 1936, Serial No. 64,105

Term of patent 14 years

To all whom it may concern:

Be it known that I, Lee B. Sapp, a citizen of the United States of America, residing at Lexington, in the county of Fayette and State of Kentucky, have invented a new, original, and ornamental Design for a Sign Board or Similar Article, of which the following is a specification, reference being had to the accompanying drawing, forming a part thereof.

I claim:

The ornamental design for a sign board or similar article, as shown.

LEE B. SAPP.
